UNITED STATES PATENT OFFICE

HARRY D. SHARPE, OF LIVERPOOL, ENGLAND, ASSIGNOR, BY MESNE ASSIGNMENTS, TO
ASSOCIATED TELEPHONE & TELEGRAPH COMPANY, OF KANSAS CITY, MISSOURI

ROTARY LINE-SWITCH CIRCUIT

Application filed December 6, 1926, Serial No. 152,796, and in Great Britain March 5, 1926. Renewed
May 2, 1929.

This invention relates to telephone systems and is particularly concerned with an improved arrangement for reducing the unguarded interval of a line or switch after it 5 has been taken into use and for ensuring that a line relay will be fully saturated when energized over high resistance junction lines.

Where a relay is energized over a high resistance junction line via the back contacts 10 of a relay energized in a local circuit as soon as an idle switch or line is seized, it has been found necessary to delay the operation of the relay energized in a local circuit to ensure full saturation of the relay energized over the 15 junction circuit. This effect has been obtained by placing a small copper slug on the core of the relay in the local circuit, but while this arrangement ensures a satisfactory saturation of the relay in the junction circuit, it 20 also causes the local circuit relay to be slow to operate and slow to release, thereby increasing the unguarded interval of the line which is marked engaged by the local circuit relay due to its slowness to operate, while 25 its increased slowness to release may cause other complications due to other relays restoring first.

According to a further feature of the invention the above results are obtained by arranging 30 the junction circuit relay to complete a locking circuit for itself over an auxiliary winding and the local circuit relay to short-circuit the auxiliary winding.

In order that the invention may be fully 35 understood and readily carried into effect, an example of the invention will be fully described as applied to hunting switches of a type which select an idle trunk responsive to a calling party removing his receiver.

40 The single figure of drawing shows a circuit diagram of a preferred embodiment of my invention.

The drawing shows a rotary line switch of the type which remains on the contacts 45 last used having a junction relay or line relay provided with an auxiliary winding which is energized in a local circuit before the switching relay operates and subsequently is short-circuited by the switching relay.

50 In the drawing, line relay L energizes over

its upper winding in series with the incoming negative and positive speaking conductors, via the back contacts of armatures 6 and 7 of switching relay K. Relay L upon operating actuates its contacts 1, 2 and 3, contact 1 closing first and followed by contacts 2 and 3. If the bank contact engaged by the test wiper P is engaged, switching relay K will be short-circuited and the driving magnet DM will energize. When the test wiper engages an idle bank contact the lower winding of relay L and the winding of relay K are connected in parallel and in series with the driving magnet DM. Relay L therefore receives an extra energization until the switching relay K operates. Relay K operates its contacts 5 and 4 before 6 and 7. Contact 4 connects earth to the test wiper P over the operated contact 2 of relay L and also short-circuits the auxiliary winding of relay L, 60 this operation rendering the relay L slow-to-release. Contact 5 prepares a holding circuit for switching relay K, while contacts 6 and 7 disconnect the energizing circuit for relay L and extend the negative and positive 65 speaking conductors to the negative and positive wipers. At this time relay L is slow-to-release since its auxiliary winding is short-circuited and relay K is maintained energized from earth, contact 4, contact 2, contact 5, 70 winding of relay K, winding of driving magnet DM to battery. Driving magnet DM however does not energize at this time owing to the high resistance of relay K, nor does it 75 energize when the lower winding of L is connected in parallel with K. When the line and release relays associated with the selected line operate one after the other, earth potential is fed back over test wiper P and serves to hold relay K energized and to guard the incoming test conductor P¹ after relay L has released.

Although the invention has been illustrated in connection with a switch of the type which remains on the contacts last used, it will be readily understood by those skilled in the art that the invention can be applied to a rotary line switch of the homing type by providing a line relay with an auxiliary 85 90 95 100

winding and with contacts such as 2 and the switching relay with contacts such as 4.

Having now described the nature of my invention and the manner in which it is to be used, what I claim as new is pointed out in the appended claims.

What is claimed is:

1. In a trunk selecting switch wherein a line relay is operated to initiate the trunk selecting movement and a switching relay is operated for seizing an idle trunk and for thereupon releasing the line relay, means for delaying the release operation of the line relay, said means including means for momentarily additionally energizing said line relay in parallel with said switching relay when the switch comes opposite an idle trunk.
2. In a trunk selecting switch, a line relay, means for operating the line relay when the switch is taken into use to indicate a busy condition of the switch and to start the trunk hunting operation, means for releasing the line relay upon the selection of a trunk, and means for momentarily delaying the releasing operation of the relay, said last means comprising a winding on the relay and means entirely within the switch for momentarily energizing and then short circuiting the winding.
3. In a trunk selecting switch, a switching relay, a line relay, means for operating the line relay, an auxiliary winding on the line relay, means establishing under predetermined conditions a locking circuit for said line relay through said auxiliary winding and contacts of said switching relay, and means controlled by the switching relay for subsequently short circuiting said auxiliary winding.
4. In a trunk selecting switch, a driving magnet, a switching relay, a line relay including an operating winding, circuit connections to said winding extending through back contacts on the switching relay, an auxiliary winding on the line relay, means establishing under predetermined conditions a circuit including the winding of the switching relay and the auxiliary winding of the line relay in parallel connected in series with the driving magnet for operating the switching relay and locking the line relay, and means controlled by the switching relay for subsequently short circuiting the auxiliary winding.
5. In a trunk selecting switch, a driving magnet, a switching relay, a line relay including an operating winding, circuit connections to said winding extending through back contacts on the switching relay, an auxiliary winding on the line relay, means establishing under predetermined conditions a circuit including the winding of the switching relay and the said auxiliary winding of the line relay in parallel connected in series with the driving magnet for operating the switching relay and locking the line relay, contacts

controlled by the switching relay for subsequently short circuiting said auxiliary winding, and connections whereby said last mentioned contacts also mark the selected trunk busy.

6. In a telephone system, a trunk selecting switch normally associated with a trunk, a line relay arranged to be operated when the switch is taken into use, means controlled by the line relay for disassociating said switch from a busy trunk and associating it with the next trunk, means for releasing the line relay responsive to the selection of and connection with an idle trunk, and means for delaying the releasing operation of the relay, said means including means for momentarily additionally energizing said line relay only during the interval between the selection of the trunk and the connection therewith.

7. In a telephone system, a trunk selecting switch having wipers normally resting on the trunk last used, a line relay, connections established when the switch is taken into use for operating the line relay, means controlled by the line relay for moving the wipers off of busy trunks, means in the switch for momentarily establishing a locking circuit for said line relay when the wipers rest upon an idle trunk and for then disabling said locking circuit independent of said wipers to release said line relay.

8. In a telephone system, a trunk selecting switch having wipers normally resting on the trunk last used, a line relay, means for energizing the line relay when the switch is taken into use and for deenergizing it responsive to the wipers resting on an idle trunk, means for insuring the complete energization of said relay prior to its deenergization when the wipers happen to rest on an idle trunk at the time the switch is taken into use, said means including means for momentarily establishing a locking circuit for saturating said relay prior to its release and means entirely within the switch for disabling said locking circuit.

9. In a trunk selecting switch, a line relay and a switching relay, an operating circuit for the line relay including back contacts of the switching relay, a holding circuit for the line relay including other back contacts of the switching relay, and a releasing circuit for the line relay including front contacts of the switching relay.

10. In a trunk selecting switch, a line relay, a switching relay, and three circuits for said line relay each including contacts of said switching relay.

11. In a trunk selecting switch comprising a line relay, a switching relay and a stepping magnet, two windings for the line relay, means for operating the line relay over one of said windings, and means responsive to the operation of the line relay for closing a circuit for the switching relay and the magnet in series, and for connecting the other of

said windings to said circuit at a point between the relay and the magnet.

12. In a trunk selecting switch equipped with a test wiper, a line relay having two windings, a switching relay, means for operating said line relay over one winding, means responsive to the operation of the line relay for completing parallel circuits for the switching relay and the other winding of the line relay, and circuit connections whereby the switching relay and the said other winding are shunted as long as the test wiper engages a busy contact.

13. In a trunk selecting switch, a line relay and a switching relay, a test wiper, a locking circuit for the line relay, and two shunt circuits for rendering said locking circuit ineffective, said first shunt circuit including contacts of the line relay and the test wiper, said second shunt circuit including contacts of the switching relay but excluding said test wiper.

14. In a trunk selecting switch equipped with a test wiper, a line relay and a switching relay, a locking circuit for said line relay, means including the test wiper for rendering said locking circuit ineffective while the wiper engages a busy contact, and means controlled by said switching relay independent of said wiper for rendering said locking circuit ineffective when the wiper encounters an idle contact.

In witness whereof, I hereunto subscribe my name this 12th day of November, A. D. 1926.

HARRY D. SHARPE.
